DESIGN FOR A COMBINATION CALENDAR STAND AND SCRATCH PAD HOLDER

Joseph S. Fisher, Bronx, N. Y.

Application July 17, 1945, Serial No. 120,761

Term of patent 14 years

(Cl. D74—1)

To all whom it may concern:

Be it known that I, Joseph S. Fisher, a citizen of the United States, residing at Bronx, in the county of Bronx and State of New York, have invented a new, original, and ornamental Design for a Combination Calendar Stand and Scratch Pad Holder, of which the following is a specification, reference being had to the accompanying drawing, forming part thereof.

The essential features of my design are shown in full lines, the printed matter shown in broken lines being merely representative of that which would appear on the calendar from month to month.

I claim:

The ornamental design for a combination calendar stand and scratch pad holder, as shown and described.

JOSEPH S. FISHER.
